A. Liddy, Esq.

UNITED STATES PATENT OFFICE.

GEORGE P. GORDON, OF BROOKLYN, NEW YORK.

IMPROVEMENT IN PRINTING-PRESSES.

Specification forming part of Letters Patent No. 43,196, dated June 21, 1864.

To all whom it may concern:

Be it known that I, GEORGE P. GORDON, of Brooklyn, in the county of Kings and State of New York, have invented, made, and applied to use certain new and useful Improvements in the Construction and Operation of Printing-Presses; and I do declare the following to be a full, clear, and correct description thereof, reference being had to the accompanying drawings, making part of this specification, and to the letters of reference marked thereon, in which—

Figure 1 is a back view of my improved printing-press. Fig. 2 is a side sectional view of the same. Fig. 3 is a side sectional view of the same; Fig. 4, detached view of wheels X X² Z Z², shaft C, and roller-frame L.

In the drawings like parts of the invention are designated by the same letters of reference.

The nature of my invention consists (*a*) in the use or employment of a single revolving ink-distributing table operating a second revolving ink-distributing table, for the purpose of thoroughly and evenly distributing the ink and supplying the same to the revolving inking-rollers; (*b*) in the use or employment of the revolving inking-rollers in combination with a revolving ink-distributing table or disk; (*c*) in the use or employment of the revolving inking-rollers in combination with a revolving ink-distributing table or disk operating a second revolving ink-distributing table or disk; (*d*) in the use or employment of a vibrating platen, vibrating substantially as shown, in combination with a stationary bed, and a revolving ink-distributing table or disk operating a second revolving ink-distributing table or disk; (*e*) in the use or employment of a vibrating platen, vibrating substantially as shown, in combination with a stationary bed, revolving inking rollers, and the revolving ink-distributing table or disk, or a revolving ink-distributing table or disk operating a second revolving ink-distributing table or disk.

To enable those skilled in the arts to make and use my invention, I will speak of its construction and operation.

A shows a frame for supporting the working parts of my improved printing-press.

B shows the bed, in which is placed the form or types, which bed is supported by the shaft C, passing through the same.

D shows the platen, hung upon the rod E,

upon which rod E it vibrates to the bed B, for the purpose of giving an impression.

F shows the driving-shaft of the press, upon which shaft is keyed the pinion G, gearing into the cog-wheel H upon the shaft C.

I is a blank crank keyed upon the opposite end of the shaft C.

The cog-wheel H and blank crank I form cranks, to which the connecting rods J are attached at one end, their opposite ends being attached, one at each end of the shaft K, inserted in the back of the platen D.

L shows a roller-frame, in which are inserted the rods M, for holding the inking-rollers N. This roller-frame is composed of the side pieces, L, held together by the cross-braces l l².

O is a support, placed directly over the shaft C and behind the bed B, for the purpose of supporting the revolving ink-distributing table or disk P. This revolving ink-distributing table or disk P is provided with the spindle p, upon which is held the toothed bevel-wheel Q. A rim, q, having ratchet-teeth cut upon it, is placed on the under side of the table or disk P, near its periphery.

R shows a second revolving ink-distributing table or disk, placed in a vertical position at the back of the press, which table or disk is provided with the spindle S, upon which is the toothed bevel-wheel T, gearing into the toothed wheel Q upon the spindle p.

U shows a surface-cam placed upon the shaft C.

V is an upright arm, provided with the pawl W, for the purpose of operating the ink-distributing table or disk P. The bed B is held firmly in a stationary position by the shoulders or tubular projections b, which are cast upon and a part of the bed-piece, being fitted firmly and permanently on each side into the frame A. Through these tubular projections b runs the shaft C, having upon one of its ends the small gear-wheel X and the large cog-wheel H. The small gear-wheel X is geared into the gear-wheel Z upon a shaft, which has upon its opposite end, inside of the frame A, the wheel X², which gears into the gear-wheel Z². The wheel Z² is fitted to and revolves upon the tubular projections b, and is attached to the revolving roller-frame L. Thus, motion being given to the shaft C, the wheel X, through the wheels Z and X², imparts

motion to the wheel Z^2 , causing the roller-frame L to revolve.

Operation: We will suppose the form or types to have been placed in the bed B and the platen D to be in the position shown in Fig. 2 of the drawings, for the purpose of receiving the sheet of paper or card to be printed, and that such sheet of paper or card has been laid upon the platen. Motion being communicated to the press, the platen D, operated by the connecting-rods J, attached as shown, vibrates upon the rod E to the bed B, for the purpose of giving an impression, and continues such vibration until an impression has been taken. An impression having been taken, the platen D, operated by the connecting-rods J, recedes from the bed B to the position shown in Fig. 2 of the drawings, necessary to allow the printed sheet to be removed and the succeeding sheet to be laid upon the platen, which, being done, the operation just described is repeated. During this operation of the platen D the inking-rollers N, held and carried in the roller-frame L, attached to the toothed wheel Z^2 , operated by means of the toothed wheels X^2 , Z, and X, have been carried over the revolving ink-distributing table or disk R, the revolving ink-distributing table or disk P, and the form or types held in the bed B, which form or types is properly inked by the rollers N in their transit. During the revolution of the roller-frame L the pawl W, (operated by the surface-cam U upon the shaft C,) acting against the rim q, rotates the ink-distributing table or disk P a certain distance, while the second revolving ink-distributing table or disk R is rotated a corresponding distance by means of the gearing Q and T.

The ink-distributing tables or disks P and

R may be supplied with ink by means of a hand-roller, and the rotation of the disks serves to thoroughly and evenly distribute the ink thus supplied.

Having thus described my invention, what I claim as new, and desire to secure by Letters Patent, is—

1. The use or employment of a revolving ink-distributing table or disk operating a second revolving ink-distributing table or disk, for the purpose of thoroughly and evenly distributing the ink and imparting the same to the inking-rollers.

2. The use or employment of the revolving inking-rollers, in combination with a revolving ink-distributing table or disk, for the purpose specified.

3. The use or employment of the revolving inking-rollers, in combination with a revolving ink-distributing table or disk, operating a second revolving ink-distributing table or disk, for the purpose specified.

4. The use of a platen, vibrating substantially as shown, in combination with a stationary bed and a revolving ink-distributing table or disk, operating a second revolving ink-distributing table or disk, for the purpose or purposes herein shown.

5. In combination with a platen, vibrating substantially as shown, the use or employment of a stationary bed, revolving inking-rollers, and a revolving ink-distributing table or disk, or a revolving ink-distributing table or disk operating a second revolving ink-distributing table or disk, for the purpose specified.

GEO. P. GORDON.

In presence of—

A. TURNERS,
A. SIDNEY DOANE.
